UNITED STATES PATENT OFFICE.

ENOCH ABNER DAVIS, OF WILSALL, MONTANA.

DISK PLOW.

Application filed December 14, 1926. Serial No. 154,766.

This invention relates to improvements in plows and more particularly to disk plows and has for its principal object to provide a device of this character in which a more perfect control of the plow is possible than has been hitherto known in the art so far as I am aware. The important features of my invention are that at all times it is possible to hold the plow in its substantial forward course despite the striking of obstacles such as stones and the like, and also maintain the proper width of the cut upon hill-sides, regardless of the degree of angularity of the hill slope, within reasonable limits. In accomplishing these objects it is not necessary that the motive power or propelling force lead off to counteract the natural tendency of the plow to swerve due to the slope of the hill. I accomplish these and other objects of my invention by the peculiar arrangement and combination of the parts as will be more fully hereinafter described and explained in the following specification, shown in the accompanying drawings and finally pointed out in the appended claims.

In the drawings:

Fig. 1 is a front elevation with parts omitted.

Fig. 2 is a rear elevation.

Fig. 3 is a side elevation with parts omitted and other parts broken away.

Fig. 4 is a top plan view.

Fig. 5 is an enlarged detailed view showing the manner of adjustably attaching the disks, partly in section taken upon the line 5—5 of Fig. 4.

Fig. 6 is a similar view showing the manner of attaching the beams to the main frame.

Fig. 7 is a similar view taken partly in section upon the line 7—7 of Fig. 4.

Fig. 8 is a detailed plan view of the steering mechanism.

Fig. 9 is a longitudinal section of the plow.

Fig. 10 is a top plan view showing the surface of the land and the position of the plow in its forward travel.

Referring now more particularly to the drawings, reference numerals 1 and 2 indicate respectively parallel beams to which are rigidly secured by means of bolts 3, one pair of axles 4 which in effect constitutes the chassis or main frame of the plow.

Secured to the outer ends of all the axles are blocks 5 which are bored through to

slidably receive supplemental axles 6 bent at right angles as best seen in Figs. 1 and 2, and upon the outer extremity of which are mounted the ground wheels 7 held in position by suitable nuts 8. All of the main axles are upturned as at 9 and the blocks 5 are bored to receive these upturned portions 9. The blocks 5 have perforations as at 10 and the upturned portions 9 are similarly perforated so that pins may be passed through the perforations and thereby secure the upturned portions 9 to the blocks 5. This adjustability of the axles will allow the plow frame or chassis to be supported at any pre-determined height above the surface of the ground, which in turn will allow the plows to cut in a corresponding depth as will be hereinafter more fully explained. Secured to each of the blocks 5 is a sector 11 with the teeth of which a tongue 12 is adapted to engage, the said tongue being slidably mounted upon a lever 13 whose outer end is pivoted at 14 to a collar 15, rigid with the block 5. 16 is a link one of whose ends is pivoted at 17 to the lever 13 and its opposite end is bifurcated as shown and pivoted at 18 to a bifurcated collar 19 through which the supplemental axle 6 slidably and rotatably passes. Between the legs of the collar 19 is a ring 20 which is secured to the shaft 6 by means of a screw 21 (see Figs. 2 and 3). All of the four ground wheels and their connections as just described are identical with each other. From the foregoing it will be seen that in addition to the adjustability of the main frame, consisting of the perforations 10 and suitable pins, a still greater flexibility of control is afforded for any one corner of the frame in case it is required to raise or lower it due to the result of the operation of the lever 13, which if its free end be forced downwardly about its center of movement 17, will cause its block 5 to be correspondingly raised. Having described the one pair of axles 4, the opposite pair 22 have their respective ends pivoted at 23 and 24 respectively. The pivotal connection 24 is in this instance in the form of a ball and socket joint, the ball member being secured to the rear axle 4 by means of bolts 25. The other axle 22 is bifurcated as indicated in dotted lines at 26 and has a pin 27 passing through a suitable aperture in the axle and a bearing 28 secured to the beam 2. A link 29 has one of

its ends pivoted at 30 to the beam 2, and its opposite end is similarly connected to the outer end of the forward axle 22. A similar link 29^a connects the rear axle 22 with the beam 2. 31 represents cross beams which pass through boxes 32 secured to the beam 2 (see Fig. 6). These boxes are flared as at 33 so as to allow a rather pivotal movement of the beams 31 within the boxes. The outer ends of the beams 31 are perforated as at 34 and there are corresponding perforations 35 in the beam 1 so that each beam 31 may be moved about the center of its box 32 to a suitable degree and pins passed through the apertures 34 and 35 so as to hold the beams in position. The opposite end of each beam 31 has adjustably secured to it a shank 32' on which is mounted a disk 36. These disks are vertically adjustable by loosening the nuts 38 which will allow the shank 32 to be moved to a desired position and then by screwing up the nuts 38 the shank will be bound tightly to its cross beam 31. The disks are also adjustable laterally as already explained. It is quite desirable that the disks be vertically adjustable because in the grinding or sharpening of the disks the diameter of some of them are decreased greater than others due to the varying hardness of the metal, and if the disks were not vertically adjustable, any of the disks of smaller diameter than the others would not plow so deeply. It will be quite clear that this objection does not exist because, due to the vertical adjustment, the lower circular edges of all the disks will be in the same horizontal plane regardless of the varying diameters of the disks.

39 indicates a plate pivoted upon a bolt 40 and through its opposite end is an aperture 41. The bolt 40 is rigid with a U-shaped plate 42 (see Figs. 1 and 4), which is bolted at 43 to the beam 2. Rigidly secured by means of the bolts 44^a, to the plate 39 is a bracket 44 upon which is pivoted at 45 a steering lever 46. 47 indicates a toothed sector rigid with the bracket 44 and with which is adapted to co-act a tongue 48 so that when the free end of the lever 46 be moved about its pivot 45 the tongue 48 will hold the lever in any of its moved positions. 49 is a link, one of whose ends is pivotally connected at 50 to the lower extremity of the lever 46 and its opposite end is similarly connected at 51 to an arm 52 which extends upwardly and outwardly from the hub of the ground wheel 7. 53 is a tie rod, each of whose ends is pivotally connected to one of the arms 52, whereby a movement of the free end of the lever 46 will cause both of the arms 52 to be actuated so as to turn both the ground wheels 7 simultaneously about their centers of movement represented by the supplemental

axles 6. This constitutes the front steering mechanism. 54 is a link, one of whose ends is pivotally connected at 55 to a projection 56 of the beam 2 and its opposite end is perforated so as to receive the bolt 40 which passes also through an aperture in one end of the plate 39, and also a similar aperture through the U-shaped plate 42. There are a plurality of apertures in the U-shaped plate 42 indicated at 56. By this arrangement it will be seen that if the bolt 40 be withdrawn the plate 39 may be moved crosswise of the frame which will of course cause the front ground wheels to be correspondingly canted, and when the plate 39 has been moved to a desired position the bolt 40 may be again inserted so as to rigidly hold the plate 39 to the U-shaped plate 42.

It will be understood that whenever the plows 36 are dropped into operative engagement with the soil, the tendency of the rear portion of the frame is to swerve outwardly into the position about as seen in Fig. 9, but the rear wheels cannot accommodate themselves to this movement. Therefore, it is necessary to provide means to bring the rear ground wheels into parallelism with the forward ground wheels. To do this I provide a shaft 60 having a steering wheel 61 on one of the ends and upon its opposite end a pinion 62, there being suitable bearings 63 for the shaft, projecting upwardly from the main frame. The pinion wheel 62 coacts with a rack 64 upon a connecting rod 65 each of whose ends is pivotally connected to a bell crank lever 66 extending outwardly from the members 6. By this arrangement the operator may grasp the handle 67 upon the wheel 61 and by rotating the shaft 60 cause both of the rear wheels to turn about their respective centers represented by the members 6.

Either draft animals or other motive power are connected to the device by any suitable means such as a chain 68. When no plowing is involved and it is necessary to move the device from place to place such as along a country road or from the field to the barn, the plows 36 are elevated above the ground by means of the levers 13. That is to say, a downward movement of the free ends of the levers 13 will cause all of the blocks 5 to rise, due to their sliding movement with respect to the members 6 which will of course raise the frame correspondingly carrying the plows with it, clear of the ground.

In operative position, all the ground wheels assume about the position as seen in Fig. 10. However, in beginning the plowing operation and before any furrow has been cut, the plows are caused to descend into the soil a predetermined distance by means of the levers 13 as already explained. The device is caused to travel steadily for

ward until the first furrow is cut around the field or area being dealt with. During the cutting of the first furrow all around, both the forward ground wheels 7 are of course travelling upon unplowed ground. After the first round or furrow is completed the right forward ground wheel travels within the furrow which has just been cut, as plainly seen in Fig. 10. For example, the dotted line indicated at A in Fig. 10 may represent the completion of the cycle or in other words the completion of the first furrow around the field. As seen in Fig. 10, the right forward ground wheel is of course still upon unplowed ground and remains so until it reaches the dotted line A, whereupon it will drop to the bottom of the furrow already made so that the next furrow or round will be plowed to the same level of the furrow just plowed.

In order to maintain the rear right ground wheel in its position with respect to the plows as seen in Fig. 10 it is desirable that the axle 4 of that wheel be adjustable transversely of the frame. I accomplish this by moving the axle 4 of that wheel to suit conditions and when so moved drop bolts through the apertures 65 in the axle 4 and beams 1 and 2.

30 The ground wheels 7 are brought to an edge, as plainly shown, so as to somewhat cut into the soil and thus assist in maintaining all the wheels in parallelism. However, since the plow when in actual operation as seen in Fig. 10 is more securely held in position by reason of the fact that the right forward ground wheel is always within the plowed furrow and against the bank of the furrow indicated at B in Fig.

40 9. Should a rock or obstacle be encountered by the front forward wheel, for example, the tendency of course would be for that wheel to rise out of its furrow in which case the forward steering lever 46 is operated to bring the forward end of the plow back into the proper position, which can be instantly done by the operator. If it were not for this quick steering mechanism, it is obvious that by the time the forward 45 wheels were righted, as indicated, quite a stretch of unplowed ground would remain.

50 Regardless of the canted position of the plow when in operative position, as seen in Fig. 10, the stress or line of force exerted by the draft animals or motor is always straight forward, as seen in Fig. 9, and parallel with the banks 9.

55 While I have shown a particular form of embodiment of my invention, I am aware 60 that many minor changes therein will read-

ily suggest themselves to others skilled in the art without departing from the spirit and scope of my invention. I therefore desire to avoid being limited to the exact form of embodiment which I have herein 65 shown and described. Having described my invention, what I claim as new and desire to protect by Letters Patent, is:—

1. An agricultural implement including a framework made up of spaced parallel bars, front and rear ground wheels for supporting the framework, axles for the ground wheels on one side of the framework and secured to both bars of the framework, an axle for the forward ground wheel on the opposite side of the framework, means for pivotally connecting the rear end of the last named axle to one of the frame bars, an axle for the remaining rear ground wheel, said axle being pivotally connected to the axle 80 of the opposite ground wheel, means whereby the framework is supported for vertical movement relative to the ground wheels, manually operable mechanism for actuating said means to vertically adjust the framework with respect to the ground wheels, plow beams supported for swinging movement on one of the frame bars, and means whereby the plow beams may be adjustably connected to the other of said frame bars. 85

2. An agricultural implement including a framework made up of spaced parallel bars, front and rear ground wheels for supporting the framework, axles for the ground wheels on one side of the framework and secured 95 to both bars of the framework, an axle for the forward ground wheel on the opposite side of the framework, means for pivotally connecting the rear end of the last named axle to one of the frame bars, an axle for the remaining rear ground wheel, said axle being pivotally connected to the axle of the opposite ground wheel, means whereby the framework is supported for vertical movement relative to the ground wheels, 100 manually operable mechanism for actuating said means to vertically adjust the framework with respect to the ground wheels, plow beams supported for swinging movement on one of the frame bars, means 105 whereby the plow beams may be adjustably connected to the other of said frame bars, mechanism adjustable with respect to one of the frame bars for steering the forward ground wheels, and manually operable means 110 supported by the framework for steering the rear ground wheels.

In testimony whereof I affix my signature.

ENOCH ABNER DAVIS.
